UNITED STATES PATENT OFFICE.

HENRY KUHN, OF ST. LOUIS, MISSOURI.

DRYING-FRAME FOR SENSITIZED PAPER.

SPECIFICATION forming part of Letters Patent No. 339,666, dated April 13, 1886.

Application filed April 30, 1885. Serial No. 164,003. (No model.)

To all whom it may concern:

Be it known that I, HENRY KUHN, a citizen of the United States, residing at St. Louis, in the county of St. Louis and State of Missouri, have invented certain new and useful Improvements in Drying-Frames for Sensitized Paper; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention has relation to drying frames for sensitized paper used by photographers; and the object of the invention is to provide a device whereby the paper after being silvered may be dried without buckling or warping, 20 and at the same time secure the edges of the paper, so that as the paper shrinks in drying it will assume a perfectly plane surface; and to these ends the novelty consists in a frame so arranged to secure the edges of the paper, as 25 will be hereinafter more fully described.

In the accompanying drawings, the same letters of reference indicate like parts of the invention.

Figure 1 is a perspective view of my frame 30 opened for the reception of the silvered paper. Fig. 2 is a cross-section of the same on the line of one of the fastening-buttons; and Fig. 3 is an enlarged sectional detail of a portion of the frame, as shown in Fig. 2.

35 A B represent two frames of similar size and shape, provided with a pair of hinges, *a a.*

C C are turn-buttons, which engage with the plate *c* in recesses *D*, and serve to clamp the frames together.

40 E is a rubber strip extending around the inner face of the frame B, and projecting a short distance above its surface.

E' is a corresponding groove in the face of the frame A, so that when the frames are

closed, as shown in Fig. 2, the rubber strip 45 will enter the groove in the opposite frame.

To use the invention, two sheets of silvered paper, after the surplus solution has been removed from them, are placed back to back, and laid in the frame so their edges will extend beyond the groove E'. The frames are then closed, and the rubber strip E presses the edge of the paper into the groove E', thus firmly securing it all around its edges. The frame is then placed aside or hung up, so the paper 55 may dry, and after it has dried it may then be placed in the fuming-box.

The advantage of handling paper in this way is, that the paper dries in the frame as smooth and flat as a drum-head, and after removal from the frame remains perfectly smooth and flat, thus insuring a perfect contact with the negative in printing, and the paper is not so liable to be soiled as if it were handled directly, as is now the case. Moreover, the paper can be cut either crosswise or lengthwise, as it does not shrink or stretch afterward.

Having thus fully described my invention, what I claim as new and useful, and desire to secure by Letters Patent of the United States, 70 is—

1. A pair of open hinged frames arranged to clamp the sensitized paper or film between them, so that the frames, by reason of their thickness, will project on either side thereof 75 at right angles to the paper to protect the surface of the same, in combination with a locking device, as set forth.

2. The combination, with the frame A B, having groove E' and rubber strip E, of the 80 turn-button C, as set forth.

In testimony whereof I affix my signature in presence of two witnesses.

HENRY KUHN.
